UNITED STATES PATENT OFFICE

MICHAEL W. McARDLE, OF CHICAGO, ILLINOIS

DESIGN FOR AN ARC HEALTH LAMP

Application filed June 17, 1929. Serial No. 31,733. Term of patent 3½ years.

To all whom it may concern:

Be it known that I, MICHAEL W. McARDLE, a citizen of the United States, residing at Chicago, in the county of Cook and State of Illinois, have invented a new, original, and ornamental Design for an Arc Health Lamp, of which the following is a specification, reference being had to the accompanying drawing, forming part thereof.

In the drawing—

Figures 1 and 2 are front and side views respectively of an arc health lamp, showing my new design.

I claim:

The ornamental design for an arc health lamp, as shown.

MICHAEL W. McARDLE.
